US0D1078401S

(12) United States Design Patent (10) Patent No.: US D1,078,401 S
(45) Date of Patent:  *Jun. 10, 2025

(54) SCRAPER

(71) Applicant: Bernard S. Moore, Brooklyn, NY (US)

(72) Inventor: Bernard S. Moore, Brooklyn, NY (US)

(*) Notice: This patent is subject to a terminal disclaimer.

() Term: 15 Years

(21) Appl. No.: 29/825,961

(22) Filed: Feb. 8, 2022

(51) LOC (15) Cl. 31-00

(52) U.S. Cl.

USPC D7/667; D27/195

(58) Field of Classification Search

USPC D7/368, 376, 381, 384, 412, 667;
D27/195

CPC .. A47J 2043/04418; A47J 43/06; A47J 43/22;
